UNITED STATES PATENT OFFICE.

JOHN W. TURNER, OF PITTSBURG, PENNSYLVANIA.

ENVELOPE SEALER AND OPENER.

SPECIFICATION forming part of Letters Patent No. 354,954, dated December 28, 1886.

Application filed October 1, 1886. Serial No. 215,071. (No model.)

To all whom it may concern:

Be it known that I, JOHN W. TURNER, a citizen of the United States, residing at Pittsburgh, in the county of Allegheny and State 5 of Pennsylvania, have invented certain new and useful Improvements in Envelope Sealers and Openers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this improvement is a simple and economically-constructed device for the convenient and rapid moistening of postage-stamps suitably for their application to envelopes, and it is also adapted for conveniently opening envelopes for the removal of their contents. These results are attained by the means illustrated in the drawings here-with filed as part hereof, in which the same letters of reference denote the same parts in 20 the different views.

25 Figure 1 represents a top view, with part broken away, of a device embodying the features of my improvement. Fig. 2 is a side view of the same, showing one of the parts in an adjusted position. Fig. 3 is a longitudinal vertical section taken on the line $\alpha\alpha$ of 30 Fig. 1. Fig. 4 represents a plate of thin sheet metal, from which the casing or body of the device is formed.

35 An inclosing-case for a sponge, B, or other suitable absorbent of moisture is formed from the plate shown in Fig. 4 by flanging or bending the plate parts a to positions at right angles to the part A. The part A' is then bent 40 toward the part A until its outer side comes in line with the edges of the flanged parts a . Before the plate is bent together in this manner the part A' is provided at its end with a bend or inclination adapted to form a depression in the body of the casing, substantially 45 as shown at A² in Fig. 3.

The flanges a are cut away at their front ends in the manner shown at a' to avoid sharp corners, and such inclined parts are provided 50 at their edges with inward bends a^3 , which engage with the casing part A' and secure the position of the same.

The sponge or other absorbent B is set between the parts A and A' before the part A' is secured in position by the bends a^3 , and a 55 pressure of the part A² on the body of the absorbent B is thus obtained that will serve the double purpose of securing the position of the absorbent within the casing and prevent the too rapid flow of moisture to the outer end of 60 the absorbent B. The casing-plate is provided with an extension, a', which is reversely bent, as shown in Figs. 2 and 3, in order to avoid sharp corners in the device.

The casing is provided at one side with a 65 flanged plate, C, secured to the part a by solder or other suitable means. The plate C is provided with a longitudinal slot, c. (Fully shown in Fig. 2.) D is the knife-blade provided at its rear end with a flange, d, which 70 projects through the slot c in the casing C, within which the blade D is arranged to slide. The flange d at the end of the blade D will prevent the latter from getting out of the casing C and secure the inward adjustment of the 75 blade D.

The absorbent B is to be made as wide or slightly wider than a postage-stamp. By placing the device in water the absorbent B will become saturated by the water, which will enter the casing at its end and between the flanges a and the part A'. Moisture may then be rapidly and uniformly applied to postage-stamps by going over the same with the exposed end of the absorbent B, and by adjusting the blade D to the position shown in Fig. 80 2 the blade may be applied to opening envelopes. The blade may be held in the position shown by a finger of the operator being set 85 against the flange d.

Having explained the features of my improvement, what I claim as new, and desire to secure by Letters Patent, is—

The slotted casing, and the blade adapted to slide therein, in combination with the casing 95 inclosing the absorbent, substantially as specified, for the purpose set forth.

In testimony whereof I have affixed my signature in presence of two witnesses.

JOHN W. TURNER.
